UNITED STATES PATENT OFFICE

OSCAR BROSIUS, OF OIL CITY, PENNSYLVANIA

HAIR CURLING BAR

Application filed August 25, 1930. Serial No. 477,693.

This invention appertains to new and useful improvements in hair curling bars in the permanent waving of hair.

The principal object of this invention is to provide a curling bar about which the hair may be tightly wrapped and subjected to an application of heat from the inside as well as the outside.

Another important object of the invention is to provide a curling bar which in use will not cause breaks in the convolutions on the bar which heretofore have resulted in an uneven parting of the hair.

These and other important objects and advantages of the invention will become readily apparent to the reader of the following specification.

In the drawings:—

Fig. 1 represents a side elevational view 20 of the unit with hair thereon.

Fig. 2 represents a side elevational view of the invention removed from the hair.

Fig. 3 represents an edge elevational view 25 of the device, looking at the perforated edge portion thereof.

Fig. 4 represents a longitudinal sectional view through the barrel of the device.

Fig. 5 represents a side elevational view of the tightening bar.

Fig. 6 represents an end elevation of the 30 device.

Fig. 7 represents a sectional view taken substantially on the line 7—7 of Fig. 2.

Fig. 8 represents a sectional view taken 35 substantially on the line 8—8 of Fig. 5.

Fig. 9 represents a side elevational view of a conventional hair curling unit showing the head of the tightening bar before the hair has been tightened on the barrel.

Fig. 10 represents a side elevational view 40 of a conventional hair curling device showing the head offset, which results from the tightening operation of the bar.

Referring to the drawings wherein like numerals designate like parts, it can be seen 45 that this novel hair curling unit includes elongated barrel 5 which is provided with a longitudinally extending ridge 6 provided with perforations 7. A protuberance in the form of an extension of the ridge 6 is pro-

vided at one end of the barrel 5 and denoted by numeral 8, the same having its edges disposed obliquely as shown in Figure 2.

An elongated cylindrical shaped bar 9 55 extends longitudinally through the barrel 5, and is provided with a longitudinally extending slot 10 at its intermediate portion. Obviously by inserting some instrument within this slot, the intermediate portion 60 of the bar can be expanded so as to frictionally engage the interior side of the barrel 9 so that the bar can only be turned with some substantial degree of effort on the part of the operator.

A wing 11 is provided at one end of the bar 9 and abuts one end of the barrel 5 while the opposite end of the bar 9 is slightly reduced as at 12 and bifurcated as at 13, the extremity of the bar 9 terminating on a plane 70 substantially flush with the extremity of the extension 8.

It can now be seen that in using the units, the hair adjacent the scalp is tied and fastened to the rod 9 by engaging the cord or 75 strand employed in the bifurcated end portion 12, after which the hair is convoluted on the barrel by forming the first convolution around the ridge extension 8.

After the hair has been convoluted along 80 the barrel, wool is used in the usual manner to preliminarily retain the hair after which the strand is used to tie the hair to the barrel 5.

It can now be seen that with the extension 85 8, the first convolution of the hair can be formed closer to the shell, and another important factor is that there is no offset head to cause breaks in the convolutions and make irregular the parting of the hair when waving is done along the sides of the part.

To elucidate this advantage, Figs. 9 and 10 disclose the conventional form found on the market. These forms usually embody a barrel 5' having a tightening bar disposed 95 therethrough and provided with a head 12' at one end, and beyond the adjacent end of the barrel 5'. This head 12' is usually slotted as at 13' and usually the barrel 5' is provided with a hollow ridge 6'. 100

Obviously when the tightening bar is rotated, the head 12' will assume this position, which obviously makes several breaks in the first convolutions, resulting in the irregular parting of the hair when working along this portion of the scalp.

- Any suitable key may be engaged with the wing 11 to facilitate the tightening operation of the bar 9, and furthermore with the perforator, steam can be expelled against the inner sides of the hair convolutions to add to the efficiency of the device by causing the hair to readily conform to the barrels and obviously retain this formation when released from the barrel.
- 15 While the foregoing specification sets forth the invention in specific terms, it is to be understood that numerous changes in the shape, size and materials may be resorted to without departing from the spirit and scope 20 of the invention as claimed hereinafter.

Having thus described my invention, what I claim as new is:

- 25 A hair waving device comprising a tube having a relatively blunt edge extending longitudinally thereof and about which hair is wrapped, said edge portion being provided with perforations through which steam can be expelled, a bar rotatably carried in the tube and provided with means at one end 30 through which the hair to be waved can be fastened, said blunt edge of the tube having an extension at one end located adjacent such means, said extension acting to prevent the hair from slipping over the end of the tube 35 during the tightening process.

In testimony whereof I affix my signature.

OSCAR BROSIUS.
